1 Claim, 4 Drawing Sheets

FIG. 1 is a view of a first embodiment of the type font;
 FIG. 2 is a view of a second embodiment of the type font;
 FIG. 3 is a view of a third embodiment of the type font; and,
 FIG. 4 is a view of a fourth embodiment of the type font.

(57) **CLAIM**

The ornamental design for the type font, as shown and described.

DESCRIPTION

abcdefghijklmnopqrstuvwxyz
